US00D740417S

(12) **United States Design Patent**
Chavan

(10) **Patent No.:** **US D740,417 S**
(45) **Date of Patent:** **** Oct. 6, 2015**

(54) **SUTURE ANCHOR**

(71) Applicant: **Dunamis, LLC**, Greenville, AL (US)

(72) Inventor: **Prithviraj Chavan**, Greenville, AL (US)

(73) Assignee: **Dunamis, LLC**, Greenville, AL (US)

(**) Term: **14 Years**

(21) Appl. No.: **29/498,900**

(22) Filed: **Aug. 8, 2014**

(51) **LOC (10) Cl.** **24-02**

(52) **U.S. Cl.**

USPC **D24/145**

(57) **CLAIM**

The ornamental design for a suture anchor, as shown and described.

DESCRIPTION

FIG. 1 is a front perspective view of a suture anchor.

FIG. 2 is a front side plan view of the suture anchor of FIG. 1.

FIG. 3 is a top plan view of the suture anchor of FIG. 1.

FIG. 4 is a bottom plan view of the suture anchor of FIG. 1.

FIG. 5 is a left side plan view of the suture anchor of FIG. 1; and,

FIG. 6 is a right side plan view of the suture anchor of FIG. 1.

1 Claim, 2 Drawing Sheets
